SAMUEL F. ESTELL, OF RICHMOND, INDIANA.

Letters Patent No. 87,765, dated March 16, 1869.

IMPROVEMENT IN SAFETY-BARREL FOR WATCHES.

The Schedule referred to in these Letters Patent and making part of the same.

To all whom it may concern:

Be it known that I, SAMUEL F. ESTELL, of the city of Richmond, and State of Indiana, have invented a new and useful Improvement in Watches; and I do hereby declare that the following is a full and exact description thereof, reference being had to the accompanying drawings, making a part of this specification, in which—

Figure 1 is a view of the main wheel, and

Figures 2 and 3 are views of the main-spring barrel.

The same letters in the different figures refer to corresponding parts of the invention.

My invention relates to an improvement in watches, for the purpose of preventing the recoil of the main-spring, in case of any accident thereto, from injuring the watch-movements.

To enable others skilled in the art to make and use my said invention, I will proceed to describe the same with reference to the drawings.

The main-wheel is recessed, forming an annular rim, or flange, near its periphery, which is grooved around its inner edge.

The main-spring barrel consists of a rim, or hoop, with one end closed. The open end of the barrel fits into the recess in the main-wheel, where it is secured in a manner similar to the bayonet-catch, by means of the pins, or projections C and C', which are admitted into the recess of the main-wheel by notches a and a', from which latter the pins are free to turn into the

groove, around the inner edge of the flange, by which the barrel is secured to the wheel.

The groove in the flange of the main-wheel is provided with a pin, b, against which one of the pins, C or C', strikes. Thus, when the watch is wound, (which is done by winding to the right in the usual manner,) a pin, C or C', is held against pin b, by which the barrel and main-wheel are locked together, and by means of which the barrel is allowed to revolve backward, independent of the main-wheel, and in the event of the sudden recoil of the main-spring, as the result of its breaking, or other cause, injury to other parts of the movement is prevented.

I do not claim connecting the main-wheel to the spring-barrel, by means of a pin and projection, in such a manner that on the breakage of the main-spring, the barrel is free to revolve, as I am aware that such a device is not new.

Having thus fully described my said invention, What I claim, and desire to secure by Letters Patent, is—

Connecting the main-wheel with the main-spring barrel, by means of the groove and pins, when the main-barrel is allowed to turn loosely on the main-wheel, in the manner and for the purpose as set forth.

SAM'L F. ESTELL.
